UNITED STATES PATENT OFFICE.

LOUIS WIEBKE AND ALBERT W. BULL, OF NEW YORK, N. Y.; SAID BULL ASSIGNOR TO
SAID WIEBKE.

ATTACHMENT FOR DUMB-WAITER SHAFTS.

1,144,516.

Specification of Letters Patent. Patented June 29, 1915.

Application filed November 7, 1914. Serial No. 870,908.

To all whom it may concern:

Be it known that we, LOUIS WIEBKE and ALBERT W. BULL, citizens of the United States, residing at New York, in the county 5 of New York and State of New York, have invented new and useful Improvements in Attachments for Dumb-Waiter Shafts, of which the following is a specification.

The general object of this invention is to 10 facilitate the operation of dumb-waiters and the like by reducing to a minimum the friction generated by the operating rope contacting with the edges of the shaft openings and thereby prevent the chafing 15 of the rope in addition to prolonging the life of the same. And to these ends the invention consists of a yoke-shaped bracket having a rotatable sheave and adapted to be mounted on the upper end of a shaft 20 opening so that the operating rope may be trained over the sheave during the operation of the dumb-waiter.

Other objects will appear and be better understood from that embodiment of our 25 invention of which the following is a specification, reference being had to the accompanying drawing forming part hereof, in which;—

Figure 1 is a vertical sectional view of a 30 dumb-waiter shaft showing our invention applied thereto, and Fig. 2 is a detail inverted perspective view of the device *per se*.

As shown in the drawings *a* indicates a dumb-waiter shaft in which a dumb-waiter 35 *b* is operated by the rope *c*, and *e* indicates one of a series of openings in the dumb-waiter shaft which provide access to the shaft from the various apartments with which they communicate. As is well 40 known, these openings *e* are formed of usual wooden framing or the like and by virtue of the sharp edges of this framing on the interior of the shaft the rope is appreciably shaved as it passes over the edges during 45 the operation of the dumb-waiter. Now, to offset this friction, we provide the device 5 which is mounted on the under side of the upper portion of the opening *e* as shown in the drawings, and thus the rope is prevented 50 from contacting with the edges as stated. This device 5 may be made of any size suitable to the shaft in which it is placed

and consists of a yoke-shaped bracket 6 and a sheave 7 which is rotatably carried by the bracket, and in point of cheapness of manufacture the bracket may be made of cast metal and thus be formed in one piece. The bracket 6 is so formed as to be provided with the bearing portions 8—8, the rope retaining portion 9 and the attaching portions 65 10—10, which are angularly disposed at opposite sides of the bearing portions as shown.

The bearing portions are preferably vertical in disposition and are in spaced relation with each other so that the sheave may be journaled therein and adapted to rotate in a vertical manner. It will be noted that the rope-retaining portion is formed by the bearing portions 8—8 which are extended 70 and are joined in a loop or eyelet; thus as the rope is trained over the sheave, the same is normally retained in position on the sheave by virtue of the rope-retaining portion. The attaching portions do not extend 75 the entire length of the bracket, but are of such length so that when the device is mounted on the dumb-waiter shaft, the rope retaining portion may extend into the shaft as shown in Fig. 1; and for the purpose of 80 securing the bracket to the frame of the opening by such means as screws or the like, the attaching portions are provided with the perforations 11 as shown.

For the purpose of readily positioning the 85 rope *c* within the bracket, the sheave 7 is detachably mounted therein. It is quite obvious that the bearing portions are bored such as indicated by 12, and thus accommodate the pin 13, which is provided at one 90 end with a suitable head 14 and is of sufficient length so that its opposite end will extend beyond the bearing as shown. The sheave is rotatably mounted on the pin 13 and thus may be readily detached from the 95 bracket, by removing the pin 13; and for the purpose of securing the pin in a fixed position in the bracket, the extending end of the pin is provided with a diametrically arranged bore 15 which accommodates a 100 cotter-pin 16 or the like, for preventing the pin 13 from being withdrawn. Thus, by virtue of the sheave being detachable, the bracket may be positioned or removed from

the dumb-waiter shaft at will, regardless of the rope, which can be readily disengaged from the bracket as described.

What we claim as new is:—

- 5 A bracket having spaced side portions provided at one edge with outstanding flanges and an intermediate curved portion merging with the said side portions, said side portions having bearings at their edges
- 10 opposite the edges at which the said flanges are located, a pin detachably mounted in

the bearings, and a sheave journaled on the pin and having their periphery lying below a plane in which the outer surfaces of the flanges lie.

15

In testimony whereof we affix our signatures in presence of two witnesses.

LOUIS WIEBKE.

ALBERT W. BULL.
